UNITED STATES PATENT OFFICE.

LEWIS E. CURTIS, OF WARREN, OHIO, ASSIGNOR TO THE YOUNGSTOWN PRESSED STEEL COMPANY, A CORPORATION OF OHIO.

METHOD OF FORMING EXPANDED-METAL CORNER BEADS.

Application filed August 10, 1923. Serial No. 656,689.

To all whom it may concern:

Be it known that I, LEWIS E. CURTIS, a citizen of the United States, residing at Warren, in the county of Trumbull and 5 State of Ohio, have invented a new and useful Improvement in Methods of Forming Expanded-Metal Corner Beads, of which the following is a specification.

The present invention relates to the art 10 of forming articles of expanded metal and more particularly to the formation of corner beads having a beadlike center portion and angularly arranged sides of expanded metal. The invention will be fully understood from the following description, illustrated by the accompanying drawings, in which:—

Figs. 1 and 2 are respectively broken plan and end views of a preliminarily grooved 20 blank;

Fig. 3 is a broken plan view of a blank as shown in Figs. 1 and 2, after slitting;

Figs. 4, 5, and 6 are diagrammatic views 25 showing successive stages of the forming of the bead or head;

Fig. 7 is a diagrammatic view illustrating means for expanding the bead; and

Figs. 8 and 9 are respectively broken end 30 and side elevations of the expanded bead.

In carrying out the present invention a blank of sheet metal of strip or ribbon form is provided with a central raised portion or inverted groove 10, preferably flattened at the top although the formation of the 35 central raised portion is not material. The portions of the blank on each side of the central raised portion 10 are indicated by the numerals 11. The blank in this stage is shown in plan in Fig. 1 and in end elevation 40 in Fig. 2.

The blank is then provided with slits in its side portions 11, as shown in Fig. 3, the slits 12 being preferably of the herringbone type. The slitted blank is then placed upon 45 or carried over a suitable forming die narrower than the internal width of the groove 10, such a die being indicated in cross-section in Fig. 4 by numeral 13. While positioned on this die, another forming die having the section illustrated at 14 engages the 50 upper surface of the sheet. The die 14 is preferably U-shaped in section, the space between the legs of the U being slightly wider than the outside width of the groove 55 portion 10, and as it engages the blank and

moves downwardly, the blank assumes the configuration shown in end elevation in Figure 5, the grooved portion 10 having its lower angles 15 brought somewhat together, partially closing the space between them, 60 while the sides 11 are forced into a position at substantially right angles with each other.

The partly formed blank is then passed through forming dies by which the center 65 bead is given a substantially circular cross-section and a portion of the metal (preferably unslotted) on each side of it is brought into substantial engagement in parallel planes for a short distance, the sides of 70 the blank being held at substantially right angles to each other. Suitable dies for this purpose are illustrated in Fig. 6, in which two laterally arranged dies 16 and an upper die 17 cause the central portion of the 75 blank, originally formed as a groove, to assume the desired form in section, as indicated at 18, the adjacent portions of the blank being forced flat against each other to form a stem in section as at 19 a die 80 member 20 holds the sides in proper angular relation.

After the blank has been formed with the center circular bead and stem, it is held in supporting dies 21, which engage the central portion of the partly formed bead on each side to prevent distortion thereof, while the slitted side portions 11 are expanded by any suitable gripping and expanding means 22. In Fig. 8 the corner bead is illustrated 90 in end elevation after it has been expanded by the operation illustrated in Fig. 7, and in Fig. 9 it is shown in side elevation. The action of the gripping and expanding means 22 brings the expanded sides 11^a into their 95 desired angular relationship, so that the resulting bead has two expanded open mesh sides 11^a meeting in a flattened stem portion 19 provided with a substantially circular bead portion 18. 100

I claim:

1. The method of forming an expanded metal corner bead, which comprises, in succession, forming a sheet with a central groove, slitting the metal at the sides of 105 said groove, partly closing the inner edges of said central groove, shaping the central groove portion and the adjacent unslotted metal to form a substantially circular bead and a flattened stem portion, and expanding 110

the metal of the slitted sides in its proper angular relation.

2. The method of forming an expanded metal corner bead, which comprises successively forming a substantially flat sheet with a central groove, slitting the metal at the sides of said groove, shaping the central groove portion and the adjacent unslitted metal to form a circular bead portion, and supporting the formed bead portion while expanding the metal of the slitted sides in their proper angular relation.

3. The method of forming an expanded metal corner bead, which comprises successively forming a substantially flat sheet with a central groove, forming herringbone slits on each side of said groove and spaced therefrom, shaping the central groove portion and adjacent unslitted metal to form a bead or head and a flattened stem portion, and expanding the metal of the slitted sides in its proper angular relation. 15 20

LEWIS E. CURTIS.
